F. DUTCHER.
RAILWAY SIGNAL TORPEDO.
APPLICATION FILED FEB. 2, 1921.

1,385,315.

Patented July 19, 1921.

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,385,315.

Specification of Letters Patent. Patented July 19, 1921.

Application filed February 2, 1921. Serial No. 441,716.

To all whom it may concern:

Be it known that I, FRANK DUTCHER, a citizen of the United States, residing at Versailles, in the county of Allegheny, and 5 State of Pennsylvania, have invented certain new and useful Improvements in Railway Signal-Torpedoes, of which the following is a specification, reference being had therein to the accompanying drawing.

10 This invention relates to improvements in railway signal torpedoes, and more particularly to a torpedo having an explosive case made by folding a sheet around the explosive charge.

15 The object of my present invention is to provide an improved manner of holding the final folds of the sheet and a rail-engaging strap to the case, whereby the usual metal clip for that purpose is omitted.

20 Another object of my present invention is to provide a torpedo which is cheap and simple of manufacture and will prevent damage and injury caused by flying fragments of metal when the charge is exploded.

25 Other objects and improvements will appear in the following description and accompanying drawings.

In the drawings:

Figure 1 is a perspective view of a torpedo embodying my invention.

Fig. 2 is a perspective view of a torpedo embodying my invention, the side of the case carrying the rail strap being shown.

30 Fig. 3 is a perspective view similar to Fig. 1, with the exception that the rail strap has not been completely fastened to the case at one end thereof and the manner of securing the strap to the case is more clearly shown.

35 Fig. 4 is an exaggerated vertical sectional view, taken longitudinally, of a torpedo embodying my invention.

Fig. 5 is an exaggerated vertical sectional view, taken transversely, of a torpedo embodying my invention.

40 Referring now to the drawings in which like parts are designated by similar reference characters, 1 designates an explosive charge which is wrapped within a sheet 2, 45 the sheet making several folds around the explosive, as at 3, thus forming a case therefor. This sheet or case 2 has a surface greater in area than the area of a longitudinal section of the explosive and has ex-

tending portions 4 and 5, which are folded 55 inward upon the case and overlap, as at 6.

To provide a means for attaching the torpedo to a rail-head or the like, I have a strap or rail attaching member 7. This strap, as here shown and in the preferred 60 form, is made of lead, but it will be readily understood that the same could be made of any suitable pliable or light spring material without departing from the spirit of my invention.

65 Those skilled in the art are well aware that the rail-engaging member must be reliably fastened to the torpedo so that when the torpedo is placed on a rail for use and struck by a moving wheel, the torpedo will 70 not be separated from the rail-engaging member and knocked from the rail without having been exploded.

In my improved torpedo, I have attached the rail straps to the case in the following 75 manner.

Two cords or strings 8 and 9 are provided. The rail strap is placed upon the case 2, across the folded lapped ends 4 and 5, as shown, and one of the cords is passed around 80 the strap, as shown at 10 in Fig. 3. The cord is then slid inwardly upon the strap until it is upon the case 2, at a point about midway of one of the folded extended portions of the case. The ends of the cord are then 85 passed in opposite directions, making several wraps of the cord around the case and strap. The ends of the cord are then brought together and fastened or tied as at 11.

It will be readily understood that the 90 other cord is applied in like manner, fastening the rail-strap at the opposite end of the case.

In practice the folded portions 4 and 5 are cemented in place, but, if desired, this 95 step can be done away with as the cords 8 and 9 not only fasten the rail strap to the case, but also bind the folded portions in proper positions.

Attention is directed to the fact that the 100 folded portions 4 and 5 overlap, as at 6. As the rail strap is carried upon these folded portions, the strap has a bend therein, as at 12, where it passes over 6. This bend, together with the previously explained manner of passing the cord around the strap, (shown at 10) prevents lateral and endwise movement or play of the rail strap upon the 105

case, thereby holding the strap in its proper position on the case.

My improvement does away with the necessity of using a plate or the like, for attaching the rail strap to the torpedo case. This is a great advantage, because the danger of damage or injury by flying particles of metal when the torpedo is exploded is greatly lessened.

10 If desired, the torpedo can be given a water-proof bath or coating to prevent dampness getting to the explosive charge which would prevent its explosion when struck.

15 Having thus described my invention, what I claim and desire to secure by Letters Patent is:—

20 1. A railway signal torpedo having a case, a rail-engaging member carried upon one side of the case, and strings wrapped first around the rail-engaging member and then around the case at opposite ends thereof and binding the rail-engaging member to the case.

25 2. A railway signal torpedo, comprising a sheet wrapped around an explosive charge to make a case therefor, the case having extended ends folded inward to overlap upon the case, a rail-engaging member upon the 30 folded portions of the case, and strings wrapped around the case and rail-engaging

member at opposite ends of the case to bind the folded portions and the rail-engaging member in place.

3. A railway signal torpedo, comprising a 35 case formed of a sheet wrapped around an explosive charge forming extended folded portions at opposite ends of the charge, the folded portions folded inward upon the case and overlapping, a rail-engaging member 40 carried upon the overlapped folded portions and bent at a point adjacent the lapped point of the folded portions, and strings at opposite ends of the case binding the folded portions and the rail-engaging member in 45 place.

4. A railway signal torpedo, of a rectangular shape, comprising a case having extended inwardly folded end portions, the end portions overlapped upon the case, a 50 rail-engaging member carried upon the folded portions and bent at a point adjacent the lap of the folded portions, strings passed around the rail-engaging member at points adjacent the ends of the torpedo case, and 55 the strings wrapped around the case, rail-engaging member, and folded end portions to hold the parts in place.

In testimony whereof I hereunto affix my signature.

FRANK DUTCHER.
